(57) **CLAIM**

We claim the ornamental design for a bottle cap, as shown and described.

DESCRIPTION

FIG. 1 is a top perspective view of a bottle cap, showing our new design.

FIG. 2 is a top plan view of the bottle cap; and,

FIG. 3 is a front plan view of the bottle cap, in which the rear, left side, and right side views are identical.

The bottom view is unornamented and not shown.
